(57) **CLAIM**

The ornamental design for a bottle with handle, as shown and described.

DESCRIPTION

FIG. 1 is a perspective view of a bottle with handle showing our new design;

FIG. 2 is a front elevational view, the rear view being a mirror image thereof;

FIG. 3 is a side elevational view taken from the right in FIG. 2;

FIG. 4 is a side elevational view taken from the left in FIG. 2; and,

FIG. 5 is a top plan view thereof.

The neck shown at the top in broken lines is for illustrative purposes only and forms no part of the claimed design.
